CLAIM

The ornamental design for a novelty windshield wiper attachment, as shown and described.

DESCRIPTION

FIG. 1 is a perspective view of the present invention illustrated on an exemplary windshield wiper blade; and FIG. 2 is a front plan view of the present invention; and FIG. 3 is a rear plan view of the present invention; and FIG. 4 is a bottom end view of the present invention; and FIG. 5 is a top end view of the present invention; and FIG. 6 is a right side view of the present invention; and, FIG. 7 is a left side view of the present invention. In the drawings, the broken lines depict a windshield wiper blade and form no part of the claimed design.
